UNITED STATES PATENT OFFICE.

JONAS L. KNOLL, OF LEBANON, PENNSYLVANIA.

DESIGN FOR A BICYCLE-FRAME.

SPECIFICATION forming part of Design No. 29,944, dated January 3, 1899.

Application filed December 12, 1898. Serial No. 699,067. Term of patent 14 years.

To all whom it may concern:

Be it known that I, JONAS L. KNOLL, a citizen of the United States, residing at Lebanon, in the county of Lebanon and State of Pennsylvania, have invented and produced a new and original Design for a Bicycle-Frame; and I do hereby declare the following to be a full, clear, and exact description of the same, reference being had to the accompanying drawing, forming a part thereof.

The drawing represents my bicycle-frame in perspective.

As shown in the drawing, the leading feature of my design consists in the backbone A, representing a flat spring-bar slightly arched and having its rear end coiled in the form of an eye a, the seat-post B representing a flat spring-bar having its lower end attached to the shaft-hanger C and its upper end to the bottom of the backbone, the front reach D representing a flat spring-bar bent in ogee form and uniting the shaft-hanger C to the front sleeve of the steering-rod. An arched

spring-brace E in the form of a flat bar has one end secured to the front reach and the other end to a holder e, mounted upon the seat-post, and an arched spring-brace F, having one end secured to the holder e and the opposite end to the eye a of the backbone A. The frame has also two braces in the form of flat bars G and H, the bar G uniting the front half of the backbone to the bottom of the sleeve of the steering-rod and the bar H uniting said front half of the backbone to the seat-post.

Having described my invention, what I claim, and desire to secure by Letters Patent, is—

The design for a bicycle-frame as herein shown and described.

In testimony whereof I affix my signature in presence of two witnesses.

JONAS L. KNOLL.
